BY *ATTY.*

UNITED STATES PATENT OFFICE.

ALBERT OLTMAN, OF EUREKA, ILLINOIS.

FARM-GATE.

1,399,372.

Specification of Letters Patent.

Patented Dec. 6, 1921.

Application filed January 17, 1920. Serial No. 352,044.

To all whom it may concern:

Be it known that I, ALBERT OLTMAN, a citizen of the United States, a resident of Eureka, in the county of Woodford and 5 State of Illinois, have invented new and useful Improvements in Farm-Gates, of which the following is a specification.

This invention has reference to new and useful improvements in farm gates.

10 The principal object of my invention is the provision of suitable tracks or rails upon which the gate, by means of rollers mounted thereon, travels from open to closed position or vice-versa.

15 A further object of my invention is the provision of obstructions at each end of the tracks or rails for the purpose of locking the gate in either open or closed position.

20 A further object is the provision of suitable means for actuating the gate when it is desired to open or close the same.

That the invention may be more fully understood, reference is had to the accompanying drawing forming a part of this 25 application, in which:—

Figure 1 is a perspective view showing a gate embodying my invention;

Fig. 2 is an enlarged typical section 30 through one of the tracks or rails, showing the character and arrangement of the obstruction for locking the gate in the open or closed position.

Fig. 3 is a side elevation of Fig. 2, and 35 Fig. 4 is an enlarged detail of the sheaves through which the rope or cable for opening the gate operates.

Like characters of reference denote corresponding parts throughout the figures.

40 1 denotes a typical farm gate provided with the long and short upstanding end portions or posts 2. 3 designates a pair of rollers suitably carried on the long and short upstanding portions or posts 2, respectively, of the gate, by means of the brackets 4. Suitably secured to the fence posts 5, 6 and 7 are the tracks 8 on which the gate travels, by means of the rollers 3. 9 designates the obstructions which lock the 45 gate within the open or closed position.

These obstructions preferably take the form of bolts secured through the tracks or rails 8, the rounded upper ends of said bolts forming effective locking means to hold the 50 gate open or closed. 10 denotes a rope or

cable suitably secured at 11 to the top rail of the gate 1; 12 and 13 denote cables or ropes, suitably secured to the cable or rope 10, and passing over the sheaves 14 and extending in opposite directions therefrom 60 and over the sheaves 15 and depending therefrom to enable the occupant of a vehicle to pull same when desirous of opening or closing the gate. The transversely extended arms 16 which are suitably secured and braced to the fence post 6, are for the purpose of supporting the sheaves 14 and 15 and are presumed to be of such length that when the oncoming vehicle is drawn by a team, there will be ample room 70 for the team between the depending ends of the rope or cables 12 and 13 and the gate, and it will not be necessary for the driver to dismount from the vehicle to open the same. This is also true after the vehicle has passed through and the occupant is desirous of closing the gate.

The sheaves 14 are swingably mounted in the clevises 17 by means of the rings 18 connected to the brackets 19 suitably secured to the transversely extended arm 16, the purpose of which will be described later.

The post 20 with the lateral connections 21 to the post 5, constitute an end stop and 85 a seat for the gate to enter when closed, to protect same against any transverse strain when in closed position. The post 22 is provided for approximately the same purpose at the opposite end of the gate. 90

In operation, see Fig. 1, the occupant of a vehicle pulls the depending end of the rope or cable 12 or 13 to open the gate. In view of the fact that the bolts 9 act as an obstruction to the opening of the gate, it will 95 be understood that the pull must be of sufficient force and duration to pass the roller 3 over the bolts 9, and impart enough momentum to the gate that it will continue to roll on the tracks toward the opened position, after the point 11 of the upper rail of the gate has passed under the sheaves 14 and the depending ends of the ropes or cables 12 or 13 have been released. Through the momentum thus acquired, the gate will 100 travel to the opened position, locking itself in that position by means of the bolts 9 at the opposite ends of the tracks 8.

It will, of course, be understood that when the gate is in the opened position that the 110

point 11 on the upper rail of the gate 1 has reached the same position relative to the sheaves 14, but on the opposite side thereof to that shown in Fig. 1. It will thus be seen that when this same operation is performed when the gate is in the opened position, that the gate will close and effectually lock itself.

What I claim is:

- 10 1. In a sliding gate, in combination, two tracks disposed in different horizontal planes, a gate having end posts, which differ in height, a roller on each post, one for each track, obstructions on each track near their opposite ends for locking the gate opened or closed, said obstructions comprising bolts secured through the tracks and having abutment heads, and a pair of cables connected to said gate for opening
- 15

and closing the same, and extending laterally from the gate.

2. In a sliding gate, in combination, two tracks disposed in different horizontal planes and round in cross-section, a gate having end posts, which differ in height, a 25 roller on each post having a dished peripheral surface to fit the contour of its track, bolts secured through each track near its opposite ends and having flat rounded heads which act to retard the rollers, and 30 the gate and hold the same in open or closed position, and cables connected to the gate to open and close the same.

In witness whereof, I have hereunto affixed my hand and seal this 13th day of 35 January, 1920.

ALBERT OLTMAN
